UNITED STATES PATENT OFFICE.

FRANK L. HARMON, OF BEVERLY, MASSACHUSETTS.

SKIVING-MACHINE.

SPECIFICATION forming part of Letters Patent No. 726,285, dated April 28, 1903.

Application filed August 1, 1899. Serial No. 725,783. (No model.)

To all whom it may concern:

Be it known that I, FRANK L. HARMON, of Beverly, in the county of Essex and Commonwealth of Massachusetts, have invented a new and useful Skiving-Machine, of which the following is a specification, reference being had to the accompanying drawings.

The machine which is the subject of this invention is designed for skiving or beveling pieces of leather near their edges, so that a folded edge may be formed by folding the skived part.

A machine for skiving or beveling the edges of leather for this purpose has been in universal use. In order to show the difference between this machine, which is old, and the machine which is alleged to be new, I name some devices employed in the former which are not employed in the latter. Said old machine contains the following devices: an overhanging arm directly in the way and in the light of an operator, under which arm the leather is moved in practice, and a mechanism comprising four shafts and six gears, some of which are made as hard as any known material and process will admit to alleviate in some degree the wear occasioned on account of their speed and some of which are made of rawhide to insure some degree of quietness; but the fact that the machine disclosed in this application has only one shaft and no overhanging arm and no worms, worm-wheels, or gears and that it can be built for less than half of the cost of making any other machine made heretofore for the purpose is proof that the machine is new and useful.

It is obvious that a machine which does not contain the above-named parts of the machine which is old cannot be regarded as a mere improvement upon such a machine, but is in itself a new and distinct type of machine; because the scheme arrangement and construction of the machine shown and described in my application, resulting in a machine with only one shaft instead of four and with no gears instead of six gears and having no overhanging arm instead of one directly in the way and in the light of an operator, is independent of the scheme arrangement and construction of the old machine referred to, wherein it is absolutely necessary to use them.

The whole construction of this machine will

be hereinafter set forth, and shown in the drawings, and these and many other novel features will hereinafter appear and will be 55 claimed in the claims appended hereto.

Figure 1 is an end elevation of the machine which is the subject of this invention. Fig. 2 is a top plan view of Fig. 1. Fig. 3 is a side elevation of Fig. 1. Fig. 4 is an end elevation showing the machine in a reversed position from the position shown in Fig. 1. Fig. 5 is a perspective detail view showing a feed eccentric or cam and a slide-bar to be vibrated by said feed eccentric or cam. Figs. 6, 7, 8, 9, and 10 are detail views of parts of a feeding device whereupon a piece of leather may be moved in practice. Fig. 11 shows another form of feeding device which may be substituted. Fig. 12 is a detail view showing 70 a rotatory disk skiving-knife and also a piece of leather in section between a presser-foot and a feeding device as presented in practice to said rotatory disk skiving-knife and also showing the shape of the skived part of the 75 leather after it is skived or beveled. Fig. 13 is a detail view of a part of a lever for supporting a part of the feeding device. Fig. 14 is a sectional detail view of a post for supporting a rod upon which a presser-foot may 80 be adjustably secured and also for supporting a part of the feeding device.

The grooved belt-wheel A is shown in Fig. 1 near the bottom and is shown in Figs. 2, 3, and 4 fast to the shaft A', shown journaled in 85 the journal-bearings of the support A⁵. The rotatory disk skiving-knife A² is shown in Fig. 12 rigidly secured upon the upper end of said shaft A' and is shown by dotted lines in Figs. 1, 2, 3, and 4. To prevent said rotatory disk skiving-knife A² (shown in Figs. 1, 2, 3, and 4) from being dangerous to an operator, it is covered, with the exception of a small part of the cutting edge, by the saucer-shaped guard A³, shown secured to the bracket 90 A⁴, shown fast to said support A⁵. Upon the lower end of said shaft A' is the eccentric or cam A⁶. (Shown in Fig. 5 and also in Figs. 1, 2, and 3.)

The slide-bar A⁷ (shown in Fig. 5) is shown 100 in Figs. 1, 2, 3, and 4 connected with said eccentric or cam A⁶ and mounted in the ways A⁸, secured to the frame B⁹, as shown in Fig. 3.

A part of the lever D⁷, with a slot therein,

is shown in Fig. 13. In Fig. 2 on the left-hand side said lever D⁷ is shown in full, and the stud C, upon which the feed-roll C' is shown rotatably secured, is adjustably secured in the slot shown in said lever shown in Fig. 13 by clamping said lever D⁷ between a collar shown on said stud C at the right of said lever D⁷ and the nut shown on said stud C at the left of said lever D⁷ by said nut, 10 and the lever D⁷ is shown pivoted to the support D¹⁸, which is really a part of the frame B⁹, by the screw D⁸.

When the cutting edge of the rotatory disk skiving-knife A² is worn away, so that it is 15 out of proper relative position with the feed-roll C', the stud C may be loosened and adjusted by hand in the slot shown in the lever D⁷ in Fig. 13 in such a manner as to place said feed-roll C' into proper relative position with 20 the cutting edge of said rotatory disk skiving-knife A².

Fig. 14 shows a portion of the post C⁹ shown in Figs. 1, 2, and 3. Upon said portion of said post C⁹ is shown the projection C⁴, in which is the hole C⁵. Said projection C⁴ is also shown by dotted lines in Figs. 1, 2, and 3. The small end of the shaft C⁶ is rotatably mounted in said hole C⁵ in said projection C⁴, as is shown by dotted lines in Fig. 3, 30 and the large end of said shaft C⁶ is rotatably mounted in the journal-bearing of the post C⁹. (Shown in Figs. 1, 2, and 4.) The friction-wheel C⁷ (shown in Fig. 3) is fast to said shaft C⁶.

35 The feed-lever B (shown in Fig. 7) is movably secured to one end of the friction-band B' (shown in Fig. 6) by the screw B², fitting loosely in a hole in said feed-lever and fast in said end of said friction-band, as shown 40 in Figs. 1, 2, 3, and 4. The link B³ (shown in Fig. 10) is movably secured to said feed-lever B by the screw B⁴, fitting loosely in the hole in the link B³ (shown in Fig. 10) and fast into the second hole from the upper end of 45 said feed-lever B. (Shown in Fig. 7.) The screw B⁵ (shown in Figs. 1, 2, and 3) extends through the slot shown in said link B³, (shown in Fig. 10,) fitting loosely in said slot, and is fast in the other end of said friction-band B'.

50 The friction-band B' is shown upon the friction-wheel C⁷ in Fig. 3, and the forked end of said feed-lever B is shown upon the block B⁶, (shown in Fig. 9,) which block is movably secured to the screw B⁷, (shown in Fig. 8,) which screw is fast to said slide-bar A⁷. (Shown in Figs. 5 and 3.)

55 A round belt (not shown) operating in the groove of the belt-wheel A rotates said belt-wheel, the shaft A' secured thereto, the rotatory disk skiving-knife A², secured to the upper end of said shaft, and the eccentric or cam A⁶, secured to the lower end of said shaft, and said eccentric or cam rotated, as aforesaid, in the opening of the slide-bar A⁷ (shown 60 in Fig. 5) causes said slide-bar to be vibrated to and fro, as is plain by Fig. 5. When said slide-bar A⁷ is thus moved to the right in Fig.

3, said screw B⁷, fast therein, and said block B⁶ on said screw are also carried toward the right in Fig. 3, and the forked end of the feed-lever B on said block B⁶ is carried by said block toward the right in Fig. 3, whereupon the upper end of said feed-lever, movably secured on the screw B², fast in one end of said friction-band B', is moved on said screw B², and the link B³, movably secured on the screw B⁴, fast in said feed-lever, is carried to the right by said feed-lever, and the screw B⁵, loose in the slot in said link and fast in the other end of said friction-band B', is moved by said link, thereby forcing the friction-band B' to grip the friction-wheel C⁷ and turn said friction-wheel toward the left in Fig. 3, thereby turning the shaft C⁶. The friction-wheel C⁷ and the gear C⁸ are fast to 85 said shaft C⁶, as shown in Figs. 1 and 3, and as said shaft C⁶ is rotatably mounted in the post C⁹ and in the projection C⁴ on the post C⁹, as above described and as shown in Figs. 3 and 14, said shaft, friction-wheel, and gear 90 are thus moved together. The gear C² is shown in Figs. 1, 2, and 3. Said gear C² is a part of the feed-roll C', which is movably secured to the stud C. (Shown in Figs. 1, 2, 3, and 4.) Said gear C² meshes into said gear 95 C⁸, so that the teeth may be forced farther into mesh without bottoming, and is moved by said gear C⁸ in the direction indicated by the arrow shown on said feed-roll C'. One end of the spring C¹⁰ (shown in Fig. 3) is fast 100 to the hook C¹¹, fast in said friction-band B', and the other end of the spring is secured to the stud C¹², fast in the bracket A⁴. When said friction-band B' is thus moved toward the left in Fig. 3, said spring C¹⁰ is thereby 105 expanded. When the feed-lever B is moved in the opposite direction, it is obvious that the friction-band B' is forced to release its grip upon the friction-wheel C⁷ and to slip upon said friction-wheel, said friction-wheel 110 being prevented from being moved by the slipping movement of the friction-band on account of the journal-bearing in the split post C⁹ (shown in Fig. 3) gripping the shaft C⁶ on account of the screw D and the spring 115 D' thereon, thereby normally causing friction between said shaft C⁶ and the bearing. By the above description of the assembling of the feed-roll C', the friction-wheel C⁷, and the devices connecting said feed-roll with said friction-wheel it is plain that said feed-roll 120 is moved intermittently.

As the spirit of my invention resides in a combination of instrumentalities, as follows—a shaft supported in journal-bearings in a 125 nearly-vertical direction, a means for rotating said shaft, a knife secured to said shaft above said journal-bearings, a feeding device, and a means for operating said feeding device combined in such a manner that a 130 piece of leather may be moved over a knife by a feeding device and the shaving cut from said leather may be moved under a knife, and so that the overhanging arm which has

formerly been employed in machines for the purpose is dispensed with, and so that a simpler machine is produced than has heretofore been made for the purpose—this part of my invention is independent of any particular form of feeding device, and therefore any feeding device may be substituted for the one used—such, for instance, as the pawl-and-ratchet device shown in Fig. 11.

10 The rod D², (shown in Figs. 1, 2, and 3,) secured in the post C⁸ by the screw D³, is adjustable up and down in said post C⁸ and may be secured at any elevation by said screw D³. The presser-foot D⁴ is adjustably secured 15 upon said rod D² by the screw D⁵, which extends through the slot D⁶ in said presser-foot and is threaded into said rod, clamping said presser-foot to said rod. The presser foot or device D⁴ is shown in Fig. 2 set as 20 near the cutting edge of said rotatory disk skiving-knife A² as possible without hitting said knife. When said knife A² is worn smaller, said presser-foot may be adjusted and secured near to the cutting edge of said 25 knife by loosening the screw D⁵ and moving said presser-foot D⁴ forward to the desired position and tightening said screw D⁵. The feed-roll C' is shown below said knife A² in Fig. 3, and when said feed-roll is turned, as and 30 by devices hereinabove described, a piece of leather may be moved by said feed-roll between the presser foot or device D⁴ and said feed-roll to said knife A². No wrinkle is formed in said leather where said leather 35 comes in contact with said knife, as is plain by the proximity of said presser foot or device D⁴ to said knife A². (Shown in Fig. 2.)

The lever D⁷, (shown in Figs. 2 and 3,) a part of which lever is shown in detail in Fig. 40 13 and to one end of which lever the feed-roll C' is adjustably secured, as above described, is pivoted at the center of said lever by the screw D⁸, which is fast in a projection on the support D¹⁸, which is a part of 45 the frame B⁹. In the other end of said lever D⁷ (shown in Fig. 3) is shown a screw D⁹, to which the upper end of the spring D¹⁰ is shown secured, and the lower end of said spring is shown secured to the screw D¹¹, 50 which is fast in said support D¹⁸.

In Figs. 1, 2, 3, and 4 the screw D¹² is shown secured into the projection of the support D¹⁸. By Fig. 3, in which the lever D⁷ is shown resting upon the screw D¹², it is 55 plain that the lever D⁷ may be adjusted and secured by said screw D¹², and as said feed-roll C' is supported by the stud C, adjustably secured in the upper end of the lever D⁷, it is also plain that by said screw D¹² said 60 feed-roll C' is prevented from striking said rotatory disk skiving-knife A².

By the above-named devices, it is plain that when a piece of leather is moved between said feed-roll C' and said presser foot or device D⁴ by said feed-roll, that said feed-roll is mechanically forced downward from 65 said presser-foot by said piece of leather far

enough to allow said piece of leather to pass through, the teeth of the gears C² and C⁸ admitting; and when thinner pieces of leather 70 are passed through, between said feed-roll C' and said presser-foot D⁴, said spring D¹⁰ causes said feed-roll to be adjusted automatically against said piece of leather. Therefore it is plain that said feed-roll C' is yieldingly 75 supported on account of said lever D⁷, the pivotal screw D⁸, and the spring D¹⁰.

In Fig. 12 the leather D^{13a} (shown in section) is shown as skived or beveled. Fig. 12 also shows that the leather after it is skived or 80 beveled passes over said rotatory disk skiving-knife A²; but by Fig. 2 it will be seen that the leather is passed over the guard A³, which guard prevents the part of the leather that is not skived or beveled from striking said knife 85 A² and also prevents said knife from being dangerous to an operator. By Fig. 12 it is also plain that the shaving D¹⁴ cut from said leather falls under said knife A².

In Figs. 1, 2, 3, and 4 the chute D¹⁵ is shown, 90 upon which chute the shavings fall.

In Fig. 3 it is shown that the support A⁵, in the journal-bearings of which support the shaft A' is journaled, is supported by the bolts D¹⁶ and D¹⁷, which bolts extend through 95 the support D¹⁸ and are rigidly fast in said support A⁵. The nuts D¹⁹ and D²⁰ are shown upon the bolts D¹⁶ and D¹⁷.

In Fig. 4 it will be observed that in the support D¹⁸ is the slot D²¹, through which the bolt D¹⁷ projects. By loosening the nuts D¹⁹ and D²⁰ (shown in Figs. 3 and 4) said support A⁵, said shaft A', rotatably mounted therein, said knife A², fast to the upper end of said shaft A', said bracket A⁴, fast to said support A⁵, and said guard A³, fast to said bracket A⁴, may be bodily moved in order to change the relative position of said knife A² to said feed-roll C', so that different bevels may be skived on said leather, and may be again secured by again tightening said nuts D¹⁹ and D²⁰.

Having thus fully described my invention as plainly and briefly as possible, I claim as follows:

1. The following combination of instrumentalities, viz: a rigid device for rotatably supporting a shaft in a nearly-vertical direction; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; a presser-foot; means for operating said feeding device.

2. The following combination of instrumentalities, viz: an adjustable rigid device for 130 rotatably supporting a shaft in a nearly-vertical direction; means for adjusting said rigid device; a shaft rotatably supported in a vertical, or nearly-vertical direction in said de-

vice for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; a presser-foot; means for operating said feeding device.

3. The following combination of instrumentali-
ties, viz: a rigid device for rotatably sup-
porting a shaft in a nearly-vertical direction;
a shaft rotatably supported in a vertical, or
nearly-vertical direction in said device for
supporting it; a rotatory disk skiving-knife
secured to the upper end of said shaft, above
said rigid device for supporting said shaft; a
guard for covering said knife, except a small
part of the cutting edge thereof; means
whereby said shaft may be rotated; a feed-
ing device; a presser-foot; means whereupon
said feeding device may be moved whereupon
a piece of leather may be moved intermit-
tently.

13. The following combination of instruments,
25 viz: an adjustable rigid device for rotatably supporting a shaft in a nearly-vertical direction; means for adjusting said rigid device; a shaft rotatably supported in a vertical, or nearly-vertical direction in said device
30 for supporting it; a rotatory disk skinning-knife secured to the upper end of said shaft, above said rigid device for supporting said shaft; a guard for covering said knife, except a small part of the cutting edge thereof;
35 means whereby said shaft may be rotated; a feeding device; a presser-foot; means whereupon said feeding device may be moved whereupon a piece of leather may be moved intermittently.

40 5. The following combination of instrumentalities, viz: a rigid device for rotatably supporting a shaft in a nearly-vertical direction; a shaft rotatably supported in a vertical, or nearly-vertical direction in said device for
45 supporting it; a rotatory disk skiving-knife secured to the upper end of said shaft, above said rigid device for supporting said shaft; a guard for covering said knife, except a small part of the cutting edge thereof; means where-
50 by said shaft may be rotated; a feeding device; means whereupon a part of said feeding device is yieldingly supported; a presser foot; means for operating said feeding device.

6. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device
60 for supporting it; a rotatory disk skinning-knife secured to the upper end of said shaft, above said rigid device for supporting said shaft; a guard for covering said knife, except a small part of the cutting edge thereof;
65 means whereby said shaft may be rotated; a feeding device; means whereupon a part of said feeding device is yieldingly supported;

a presser-foot; means for operating said feeding device.

7. The following combination of instrumentalities, viz: a rigid device for rotatably supporting a shaft in a nearly-vertical direction; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means whereupon a part of said feeding device is yieldingly supported; a presser-foot; means whereupon said feeding device may be moved whereupon a piece of leather may be moved intermittently. 75 80 85

8. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means whereupon a part of said feeding device is yieldingly supported; a presser-foot; means whereupon said feeding device may be moved whereupon a piece of leather may be moved intermittently.

9. The following combination of instrumentalities, viz: a rigid device for rotatably supporting a shaft in a nearly-vertical direction; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means for adjusting a part of said feeding device; a presser-foot; means for operating said feeding device. 110 115

10. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means for adjusting a part of said feeding device; a presser-foot; means for operating said feeding device. 120 125 130

11. The following combination of instrumentalities, viz: a rigid device for rotatably supporting a shaft in a nearly-vertical direc-

tion; a shaft rotatably supported in a vertical, or nearly-vertical direction in said device for supporting it; a rotatory disk skiving-knife secured to the upper end of said shaft, 5 above said rigid device for supporting said shaft; a guard for covering said knife, except a small part of the cutting edge thereof; means whereby said shaft may be rotated; a feeding device; means for adjusting a part of 10 said feeding device; a presser-foot; means whereupon said feeding device may be moved whereupon a piece of leather may be moved intermittently.

12. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means for adjusting a part of said feeding device; a presser-foot; means whereupon said feeding device may be moved whereupon a piece of leather 25 may be moved intermittently.

13. The following combination of instrumentalities, viz: a rigid device for rotatably supporting a shaft in a nearly-vertical direction; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small 30 part of the cutting edge thereof; means whereby said shaft may be rotated; a feeding device; means whereupon a part of said feeding device is yieldingly supported; means for adjusting a part of said feeding device; a presser-foot; means for operating said feeding device.

14. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; means whereupon a part of 45 said feeding device is yieldingly supported; means for adjusting a part of said feeding device; a presser-foot; means for operating said feeding device.

15. The following combination of instrumentalities, viz: a rigid device for rotatably supporting a shaft in a nearly-vertical direction; a shaft rotatably supported in a vertical, or nearly-vertical direction in said device for supporting it; a rotatory disk skiving-knife secured to the upper end of said shaft, above said rigid device for supporting

cal, or nearly-vertical direction in said device for supporting it; a rotatory disk skiving-knife secured to the upper end of said shaft, 70 above said rigid device for supporting said shaft; a guard for covering said knife, except a small part of the cutting edge thereof; means whereby said shaft may be rotated; a feeding device; means whereupon a part of 75 said feeding device is yieldingly supported; means for adjusting a part of said feeding device; a presser-foot; means whereupon said feeding device may be moved whereupon a piece of leather 80 may be moved intermittently.

16. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, 85 except a small part of the cutting edge thereof; means whereby said shaft may be rotated; a feeding device; means whereupon a part of said feeding device is yieldingly supported; means for adjusting a part of said feeding device; a presser-foot; means whereupon said feeding device may be moved whereupon a piece of leather 90 may be moved intermittently.

17. The following combination of instrumentalities, viz: a friction-wheel; means for rotatably supporting said friction-wheel; a friction-band connected with said friction-wheel; a spring connected with said friction-band and exerting power thereon; a lever movably 105 connected with said friction-band; a link movably connected with said lever and said friction-band; means for vibrating said lever.

18. The following combination of instrumentalities, viz: an adjustable rigid device 110 for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting said shaft; a guard for covering said knife, except a small part of the cutting edge thereof; means whereby said shaft may be rotated; a feeding device; a presser-foot or device; means for adjusting said presser-foot or device toward said knife; means for adjusting said presser-foot vertically; means for operating said feeding device.

19. The following combination of instrumentalities, viz: an adjustable rigid device for rotatably supporting a shaft in a nearly-vertical direction; means for adjusting said rigid device; a shaft rotatably supported in a vertical, or nearly-vertical direction in said device for supporting it; a rotatory disk skiving-knife secured to the upper end of said shaft, above said rigid device for supporting

said shaft; a guard for covering said knife, except a small part of the cutting edge thereof; means whereby said shaft may be rotated; a feeding device; a presser-foot or device; means for adjusting said presser-foot or device toward said knife; means for adjusting said presser-foot vertically; a connecting de-

vice comprising a cam, or eccentric and a device adapted to be operated thereby, between said shaft and a part of said feeding device.
